UNITED STATES PATENT OFFICE

FREDERICK J. RAYFIELD, OF CHICAGO, ILLINOIS, ASSIGNOR TO CHAMPION PNEUMATIC MACHINERY COMPANY, OF CHICAGO, ILLINOIS, A CORPORATION OF ILLINOIS

PUMP

Application filed November 15, 1929. Serial No. 407,388.

This invention relates to pumps, particularly to vertical reciprocating double action pumps for delivering fluid such as water under high pressure.

5 An important object of the invention is to provide an improved arrangement for lubricating automatically the various operating parts of the pump, the feature of the lubricating arrangement being the positive pumping or centrifugal discharge of oil from a main oil chamber through the connecting rod and from there through the wrist pin to the cross head.

10 Another important object of the invention resides in simplified arrangement for the plunger cylinder, particularly in a lining therefor which can be readily removed and replaced without disturbing other elements of the pump.

15 Another feature resides in improved valve structure and arrangement for controlling the flow of fluid through the pump, improved unitary valve structures being provided which are readily removable for inspection or repair.

20 Other features of construction, arrangement and operation will be apparent from the following specification and the accompanying drawings. On the drawings

25 Figure 1 is a vertical transverse section through the pump;

Figure 2 is an enlarged section on plane II-II of Figure 1;

30 Figure 3 is an enlarged section on plane III-III of Figure 1;

Figure 4 is an enlarged vertical section through the connecting rod and the eccentric; and

35 Figure 5 is a developed view of the cylindrical surface of the eccentric showing the oil collecting and pumping grooves.

The pump frame comprises the lower or base part 10 and the upper part 11, which parts may be in the form of castings and detachably secured together. Within the base part is the crank chamber 12 which also acts as a lubricating oil reservoir through which oil may be supplied through a plugged opening 13. A crank shaft 14 is journalled in

50 opposite sides of the base and carries a driv-

ing pulley 15. Secured on the shaft is an eccentric member 16 received by the head 17 on the lower end of the connecting rod 18, which, at its upper end, has the transverse opening 19 for receiving the wrist pin 20 extending diametrically of and supported by the cross head structure 21. The wrist pin 20 may be anchored in either the crosshead or the connecting rod. The cross head is cylindrical and is guided in the cylindrical guide sleeve 22 supported by a transverse wall 22' forming part of the base 10. The cross head has a top 23 which threadedly receives the lower end of the piston rod 24 extending downwardly from the plunger structure. The piston rod extends through a packing gland structure 25 supported by a transverse wall 26 forming part of the frame 11.

55 A cylinder 27 for the plunger structure 70 forms part of the frame 11 and has its lower end contracted slightly to form a seating shoulder or ledge 28 for the liner or bushing 29 of brass or other suitable material. At its upper end the cylinder has the threaded counterbore 30 for receiving the shouldered collar 31 for engaging the upper end of the liner 29 to hold it securely within the cylinder against its seat 28.

60 The plunger structure comprises upper and lower oppositely directed and leather washered plunger members 32 and 33 which may be adjusted on the threaded upper end of the piston rod and held in place by upper and lower nuts 34 and 35. The plunger is 75 thus double acting.

65 The upper wall 36 of the frame part 11 has the opening 37 whose diameter is larger than that of the cylinder liner 29 and its securing collar 31 so that the collar and liner 90 may be readily removed from the cylinder for replacement or repair. A cover plate or plug 38 is provided for the opening 37 and is locked in closed position by a suitable yoke structure 39. A suitable gasket 40 may be 95 provided for the cover plate to prevent leakage.

70 Between the upper side wall section 41 of the frame part 11 and the cylinder 27 is an intermediate wall 42 which with the cylin- 100

der wall forms an intake chamber 43 connected with a fluid intake pipe 44. The opposite side wall section 45 of the frame part 11 and the cylinder wall form the discharge chamber 46 connected with the discharge pipe 47. Between the upper end of the cylinder and the top wall 36 of the frame 11 is the fluid passage 48 whose connection with the intake chamber 43 is by way of a port 49 through the wall 42, this port being controlled by a check valve structure A. Between the lower end of the cylinder and the wall 26 is the fluid passage 50 whose communication with the intake chamber 43 is by way of a port 15 passage 51 which is controlled by a check valve structure B. The connection of the passageway 48 with the discharge chamber 46 is through a port 52 controlled by a check valve structure C, and the connection of the passage 50 with the discharge chamber is through a port 53 controlled by a check valve structure D.

The valve structures are all alike and the details of construction are clearly shown in Figure 3. Each valve structure comprises a cylindrical cage 54 open at its inner end and closed at its outer end and having external threads 55 for detachably seating it in its respective supporting wall. Figure 3 shows the valve structure C and its cage is seated in the wall 45. An abutment flange 56 on the cage limits its inward movement and also assists in sealing against leakage. Telescopically engaging in each cage is a sleeve 57 whose outer end 58 forms a valve head presenting an annular valve ridge 59 for seating against a bushing 60 within the respective fluid port. In Figure 3, the bushing is within the port 52.

Within each sleeve is a compression spring 61 abutting against the valve head and the end of the cage and tending to force the valve head outwardly against its seating bushing. At its inner end the cage of each valve structure has passageways 62 which register with passageways 63 through the valve sleeve when the valve head is in seating engagement with its seat bushing.

Describing now the operation of the pump, when the plunger structure is moving downwardly there will be suction effect above the plunger structure and in the passage 48, and this suction effect will hold the valve of the valve structure C firmly against its seat to close the port 52. The suction effect will also be communicated to the interior of the valve structure A through the registering passages 62 and 63, and the valve will be moved from its seat and will then be held from its seat while the fluid is being drawn from the intake chamber 43 through the port 49 and into the passage 48. As the plunger moves downwardly, a charge of fluid is drawn in its wake, and in advance of the plunger the fluid is being forced into the

passage 50, the pressure acting against the valve head of the valve structure D and opening the port 53 for the flow of the fluid into the discharge chamber 46 and out through the discharge pipe 47. The pressure is also communicated to the interior of the valve structure B through the registering passageways 62 and 63 of the valve structure and the pressure will then assist the valve spring in holding the valve head to its seat to close the port 51. When the plunger starts its upward stroke, the valve D will be closed and also the valve A, and valves B and C will be open so that fluid can be taken into the passage 50 in the wake of the rising plunger, and the fluid will be discharged from above the plunger through the passage 48, port 52, discharge chamber 46, and the discharge pipe 47.

The lower part of the base 10 within the chamber 12 forms an oil sump for lubricating oil through which the eccentric 16 and eccentric head 17 pass during operation of the pump. In the surface of the eccentric 16 are sets of oil grooves 64 and 65 extending from the opposite sides of the eccentric and converging to meet and communicate with a recess or pocket 66 in the eccentric head 17. The eccentric rotates in the direction indicated by arrows on Figs. 1 and 3 and as it rotates and plunges through the oil, the oil grooves of each set scoop up oil at their outer ends and the pressure and centrifugal action cause this oil to flow along the grooves and into the pocket 66 from where the oil is forced up through the passageway 67 extending longitudinally through the connecting rod. The bearing opening 19 for the connecting rod is lined with a bushing 68 surrounding the wrist pin 20 which is shown as being tubular, and the bushing and wrist pin have passages 70 and 71, respectively, registering with the duct 67. The oil which is forced up through the duct 67 thus flows into the tubular wrist pin and out at the ends thereof and between the cross head 21 and its guide sleeve 22 to lubricate the bearing surfaces of the cross head and pin.

At the upper end of the guide sleeve and surrounding the cross head is the annular recess 72 which collects surplus oil carried upwardly with the cross head, and on top of the cross head is the annular trough 73 which receives the oil from the recess during upstroke of the cross head, the oil flowing from the trough through the passage 74 to the interior of the cross head and back to the oil sump.

The eccentric depressions or pockets 75 in the sides of the eccentric 16 serve to throw oil from the sump to the bearings for the shaft 14.

For the plunger structure and piston rod no oil lubrication is necessary as the water

or other fluid pumped will supply the necessary lubrication.

A guard or hood 77 is secured to the piston rod above the cross head which deflects from the cross head any fluid which might leak out of the gland 25 and conducts it downwardly to the wall 22' from where it flows to the exterior of the pump through openings 78. Thus no water can get to the cross head or to the crank case.

I thus provide an efficient lubricating system in which the oil is forced or pumped centrifugally through the connecting rod and through the wrist pin to the cross head bearing, the grooves in the eccentric not only functioning to pump and force oil upwardly through the connecting rod but also to uniformly distribute the oil between the eccentric and the eccentric head for efficient lubrication.

My improved pump structure is of simple and economically manufactured design, and all the operating parts are readily accessible for inspection, repair, or replacement.

Changes and modifications can be made without departing from the scope and principles of my invention, and I do not, therefore, desire to be limited except as necessitated by the prior art.

I claim as follows:

1. The combination of a supporting frame providing an oil well at its lower end, a drive shaft extending through said well, an eccentric on said shaft, a cross head guide above said shaft, a cross head reciprocal in said guide, a plunger above said guide connected with said cross head, a connecting rod receiving said eccentric at its lower end, a wrist pin connecting the upper end of said connecting rod with said cross head, said connecting rod having an oil duct extending the entire length thereof there being oil grooves in the bearing space of said eccentric extending circumferentially along said surface from the sides of the eccentric and terminating intermediate the sides, oil being scooped up by said groove during operation of the shaft and forced therefrom into and through the duct in the connecting rod, said wrist pin having passageways communicating with said duct to convey oil therefrom to the bearing surface of the cross head, and means for returning oil working past the crosshead to the interior thereof.

2. The combination of a supporting frame providing an oil well at its lower end, a drive shaft extending through said well, an eccentric on said shaft, a cross head guide above said shaft, a cross head reciprocal in said guide, a connecting rod receiving said eccentric, a wrist pin journaling said connecting rod on said cross head, there being oil grooves in the surface of said eccentric, said connecting rod having an oil duct communicating with said oil grooves, said wrist pin having

a duct for conducting oil from said connecting rod to the cross head bearing, said guide at its upper end having an annular recess surrounding said cross head, said cross head having an annular trough at its upper end for receiving surplus oil from said recess, and said cross head having a passageway connecting said trough with the interior of said cross head for the return of the collected oil to said oil well.

In testimony whereof I have hereunto subscribed my name at Chicago, Cook County, Illinois.

FREDERICK J. RAYFIELD.
